DESIGN FOR A COMBINED CIGARETTE DIS- PENSER AND MATCH HOLDER

William T. Korn, New York, N. Y.

Application September 24, 1945, Serial No. 122,282

Term of patent 7 years

(Cl. D85—2)

To all whom it may concern:

Be it known that I, William T. Korn, a citizen of the United States of America, residing in New York city, county of New York, and State of New York, have invented a new, original, and ornamental Design for a Combined Cigarette Dispenser and Match Holder, of which the following is a specification, reference being had to the accompanying drawings, forming part thereof, wherein

I claim:

The ornamental design for a combined cigarette dispenser and match holder, substantially as shown.

WILLIAM T. KORN.
